Inventor:
John R. Allen.
By: May W. Zabel Atty.

UNITED STATES PATENT OFFICE.

JOHN R. ALLEN, OF CHICAGO, ILLINOIS, ASSIGNOR TO STACKHOUSE & ALLEN, OF CHICAGO, ILLINOIS, A PARTNERSHIP CONSISTING OF JOHN H. STACKHOUSE AND JOHN R. ALLEN.

ELECTRICAL FIXTURE.

Application filed May 31, 1923. Serial No. 642,555.

My invention relates to electrical fixtures, and more particularly to an electrical fixture having a bell portion to which cap members of sockets may be secured, and to the particular means of securing such a cap member to a bell member or other similar apertured member in a fixture of this character so as to permanently and rigidly secure said members together in a simple and efficient manner and at a small cost. It is a further purpose of the invention to provide means for securing a cap member to a bell-like portion of an electrical fixture, whereby the means for clamping said parts together also prevents relative rotation thereof, and to provide a finishing sleeve for said fixture, whereby an insulating lining is held in the cap, as well as the securing means is concealed. Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art, and as would fall within the scope of the claims.

In the drawings:

Fig. 1 is a side elevation partly in section of my improved electrical fixture showing the cap secured in position;

Fig. 2 is a view looking into the open end of the cap in Fig. 1, said cap being shown with the insulating lining removed;

Fig. 3 is a section taken on the line 3—3 of Fig. 2; and

Fig. 4 is a view in fragmentary section showing the parts of the device as separated to more clearly show the construction of the various parts thereof.

Referring in detail to the drawings, in Fig. 1 is shown a bell portion or similar portion of an electrical fixture 10, which may be provided with a cap 11 held thereon in any suitable manner. Said bell portion 10 is provided with openings 12, and cap members 13 for the ordinary lamp socket are secured to said bell portion 10 with the openings 14 in said cap member in alignment with the openings 12. New and improved means is provided for securing the cap mem-

bers 13 to the bell portion 10, said means comprising prongs or tongues 15 on said member 10, and similar prongs or tongues 16 on the member 13.

As will be clear from Fig. 2, the prongs 16 are so formed that the cuts at the sides thereof extend inwardly beyond the circular edge portion bounding the opening 14, thus forming notches 17. The prongs 15 are formed in a similar manner on the member 10, the notches in the member 10 being indicated at 18 in Fig. 3.

It will be seen upon reference to Fig. 3 that the prongs 15 extend over the prongs 16 when bent into position, and that due to the notches 17 and 18 said prongs 15 and portions of the material of the member 10 will be located in the notches 17, thus not only holding the cap members 13 in position on the member 10 but also preventing relative rotation of said members 10 and 13. In practice the openings 12 and 14 and the prongs 15 and 16 are formed by one punching operation, and are also bent into the shape shown in Fig. 3 by said operation.

The separated arrangement shown in Fig. 4 has been shown merely to illustrate the construction of the various parts to more clearly bring out how they interengage so as to lock the parts in fixed position. The cap members 13 are provided with the usual insulating lining 19 which is held in position by means of a sleeve 20 which is flanged over as shown at 21 and 22 to hold said lining in position in the cap, said sleeve with the flanges 22 also giving a finished appearance to the device and providing smooth surfaces where the conductors extend from the bell 10 into the caps 13.

Having thus described my invention, what I desire to claim and secure by U. S. Letters Patent is:

1. In a device of the character described, a bell portion and a member having a reduced portion secured thereto by means of interlocking fingers, an insulating lining for said member and a finishing sleeve covering said fingers and holding said lining in position.

2. In an electrical fixture, a body portion and a lamp socket cap and means for securing said cap to said body portion comprising hook prongs on said body portion engaging said cap, said cap having an insulating

lining and a finishing sleeve covering said hook prongs and holding said lining in position.

3. In an electrical device, a cup-like body member, a lamp socket cap member, and means for permanently and non-rotatably securing said members together, comprising hooklike portions struck from the edges of aligning openings in said members inter-folded and clinched together.

4. In an electrical device, a cup-like body member, a lamp socket cap member, and means for securing said members together, comprising hooklike portions on said members inter-folded and clinched together, said clinched portions resting in recesses in said members to prevent relative rotation thereof.

In witness whereof, I hereunto subscribe my name this 10th day of May A. D., 1923.

JOHN R. ALLEN.
